(57) CLAIM

The ornamental design for a hair accessory organizer, as shown and described.

DESCRIPTION

FIG. 1 is a diagonal, perspective view of a hair accessory organizer depicted in a closed configuration showing my inventive design;

FIG. 2 is a front view thereof;

FIG. 3 is a side view thereof, shown from a right angle;

FIG. 4 is a second top view thereof; and,

FIG. 5 is a back view thereof.

The broken lines shown in the figures represent stitching and form part of the claimed design. The dot-dash broken line showing of the bottle depicts environment that forms no part of the claimed design.
